UNITED STATES PATENT OFFICE

125,930

DESIGN FOR A MANTELPIECE ORNAMENT OR SIMILAR ARTICLE

Stephen Tearl, Wilmington, Del.

Application July 3, 1940, Serial No. 93,415

Term of patent 3½ years

To all whom it may concern:

Be it known that I, Stephen Tearl, a citizen of the United States, residing at Wilmington, in the county of New Castle and State of Delaware, have invented a new, original, and ornamental Design for a Mantelpiece Ornament or Similar Article, of which the following is a specification, reference being had to the accompanying drawings, forming part thereof:

piece ornament or similar article, showing my new design.

I claim:

The ornamental design for a mantelpiece ornament or similar article, as shown.

STEPHEN TEARL.
